US00D967534S

(12) **United States Design Patent** (10) Patent No.: **US D967,534 S**
(45) Date of Patent: **** Oct. 18, 2022**

(54) **COMBINED SHAVER AND CLEANING UNIT**

(71) Applicant: **KONINKLIJKE PHILIPS N.V.**,
Eindhoven (NL)

(72) Inventors: **Jos Van Roosmalen**, Amsterdam (NL);
Frank Verbrugge, Rosmalen (NL);
Jens Andersson, Amsterdam (NL);
Roel Krooshof, Bilthoven (NL); **Simon Van Anken**, Amsterdam (NL); **Peter Gal**, Amsterdam (NL); **Lieven Adriaenssen**, Vilvoorde (BE); **Roshan Hakkim**, Amsterdam (NL); **Mingshuo Zhang**, Amstelveen (NL)

(73) Assignee: **KONINKLIJKE PHILIPS N.V.**,
Eindhoven (NL)

(**) Term: **15 Years**

(21) Appl. No.: **29/723,221**

(22) Filed: **Feb. 5, 2020**

(30) **Foreign Application Priority Data**

Sep. 3, 2019 (EM) 006809323

(51) **LOC (13) Cl.** **28-03**

(52) **U.S. Cl.**

USPC **D28/50; D32/1**
